GRATER

Filed Sept. 28, 1921

Jacob I. Robin
INVENTOR
BY
Mark S. Dohmeny
ATTORNEY

UNITED STATES PATENT OFFICE.

JACOB I. ROBIN, OF NEW YORK, N. Y.

GRATER.

Application filed September 28, 1921. Serial No. 503,769.

To all whom it may concern:

Be it known that JACOB I. ROBIN, a citizen of the United States of America, residing at New York, in the county of New York and State of New York, has invented certain new and useful Improvements in Graters, of which the following is a specification.

The present invention relates to kitchen utensils for grating vegetables or the like.

Graters of the hitherto known construction have the drawback that the perforated indentations on the grating surface become quickly clogged up with the grated material causing the latter to accumulate around the indentations and ceasing to operate. The work then has to be discontinued and the surface thoroughly cleaned.

One object of my invention is to provide a construction whereby this drawback will be obviated.

Another object of my invention is to provide a construction whereby grating will be rendered more convenient and injury to the hand prevented.

With these and other objects in view my invention consists in the provision of a grater which, in addition to the usual perforations, has a plurality of comparatively large openings even with the face of the grater to permit free and continuous passage of the grated material.

With the hitherto used graters the indentations are arranged in parallel rows inclined at 45° to the horizontal whereby longitudinal gaps between the indentations are formed. Owing to these gaps the article when grated has to be frequently turned into new positions to bring the ungrated parts thereof in range with the indentations. According to my invention this drawback is overcome by selecting an angle of 60° for the rows of indentations, whereby continuous longitudinal gaps will be avoided.

To facilitate the grating operation and prevent injury to the hand of the user I provide a base on which the grater can be removably supported at an elevation from a dish or receptacle receiving the grated material, and a movable holder for the article to be grated.

My invention also consists in the novel construction, combination and arrangement of parts as will be hereinafter more fully described and defined in the appended claims.

In the accompanying drawing which

forms part of this specification and in which similar reference characters denote corresponding parts, Fig. 1 is a vertical section of the grating utensil; Fig. 2 is a section on line 2—2 of Fig. 1; and Fig. 3 is a section on line 3—3 of Fig. 1.

10 denotes a frame or stand consisting of a substantially rectangular base plate 10' and legs 10². The legs at one end of the base plate are made a little shorter than at the opposite end so that the base plate will extend longitudinally in a slanting position. The base 10' is provided with a longitudinally extending opening 10^a having circumferentially curved ends and which is adapted to form a socket for the grater proper 11. The grater proper 11 is in form of a shallow dish, the free edge of the marginal wall 11^a of which is bent horizontally. The bottom of the dish corresponds in size and shape with that of the opening 10^a and the bent edge of the marginal wall 11^a is adapted to engage the upper face of the base 10' around the opening 10^a and to thereby removably support the grater in position.

As usually the grater is provided longitudinally with a plurality of parallel rows of equidistantly distributed perforated indentations 11', 11², 11³ . . . . But instead of running at an angle of about 45° to the horizontal, these rows are arranged at an angle of more than 45°, preferably 60°, whereby continuous longitudinal gaps between adjacent indentations will be avoided. The advantage of such construction is that the article to be grated will not need to be turned to different positions while moved there and back on the grating surface, as all parts in frictional contact with the grater will find an indentation or indentations by which they will be grated.

In addition to the perforated indentations, I provide between each two adjacent rows thereof, a row of comparatively large openings 12', 12², 12³ . . . made even with the upper face of the grater and which serve as passages for the grated material. Owing to these passages the grated material will be allowed to continuously pass through the grater and clogging of the grating surface will be avoided.

Slidably mounted on the base 10' is a member 13 for holding the article to be grated. This holder may be in form of a plate extending longitudinally over the grater and formed centrally with an open-

ing 13' in which the article to be grated is deposited. The side edges 13³ of this plate are bent downwardly to form resilient guide members adapted to frictionally engage the 5 sides of the base 10'. This plate 13 may be extended at its ends as at 13² so as to act as shields covering the grater and preventing the grated material from being thrown into the surrounding space.

10 To avoid the necessity of holding the article by hand during the grating and also to facilitate the grating operation, a tubular body 14 open at both ends may be suitably fixed to the plate 13 to project 15 upwardly around the opening 13'. This tubular body will serve both as a pocket for the article to be grated, and as a handle whereby the slideable plate 13 may be manipulated.

20 Removably and slidably fitted in said tube 14 may be a plunger 15 in form of a second tube, the bottom 15' of which may be roughened. By means of this plunger the article contained in the pocket 14 can be 25 pressed into frictional contact with the grating surface.

Projecting from the frame 10 below its base plate 10' may be a chute 16 over which the grated material will be conveyed into a 30 receptacle located below the grater.

According to the present example the tube 14 is fastened to the plate 13 by clamping arms 13⁴ engaging an annular flange 14' formed at the bottom of the tube.

35 It is, of course, understood that the construction may be modified in various ways without departing from the spirit of my invention.

What I claim and desire to secure by Letters Patent is:—

1. In a device of the character described, an elevated base having a longitudinal opening, a dish shaped grater formed with a marginal flange adapted to engage the marginal edge of said opening and to removably support said grater on said base, a removable slide on said base formed with an opening to receive the article to be grated, means on said slide engaging the sides of said base to guide it longitudinally and a tubular member removably clamped to said slide over said opening to form a receptacle for the article to be grated and serve as a handle.

2. In a device of the character described, an elevated base having a longitudinal opening, a dish shaped grater formed with a marginal flange adapted to engage the marginal edge of said opening and to removably support said grater on said base, a removable slide on said base formed with an opening to receive the article to be grated, means on said slide engaging the sides of said base to guide it longitudinally, a tubular member to form a receptacle for the articles to be grated and serve as a handle and clamping means on said slide to removably clamp said tubular members to said slide.

In testimony whereof I affix my signature in presence of two witnesses.

JACOB I. ROBIN.
